UNITED STATES PATENT OFFICE.

DAVID TALMAGE, OF BROOKLYN, NEW YORK.

MEANS FOR PLAYING ON THE KEYBOARDS OF MUSICAL INSTRUMENTS.

Application filed September 23, 1924. Serial No. 739,274.

In one aspect, my invention relates to a device for playing on the keyboard of a musical instrument, such as a piano, which may be used by anyone either with or without technical musical knowledge or training, to improvise original solos and also to improvise accompaniments to songs or instrumental selections.

In another aspect, my invention provides in conjunction with the said device, means affording to the operator of the said device an indication of the way in which the device should be manipulated to secure the desired results.

Other objects of my invention will appear in the specification and will be particularly pointed out in the claims.

My invention will best be understood by reference to the accompanying drawings, in which I have illustrated a preferred embodiment thereof and in which Fig. 1 is a perspective view of the keyboard of a musical instrument, such as a piano, with means embodying my invention associated therewith; Fig. 2 is a view similar to Fig. 1, illustrating the manually operated device in a different position with relation to the keyboard from that illustrated in Fig. 1; Fig. 3 is a plan view of an indicator chart which may be placed on the keyboard in accordance with my invention; Fig. 4 is a plan view of a song chart which may also be used as part of my invention; Fig. 5 is a detail view illustrating one of the fingers adjustably held in position in the frame of the device; Fig. 6 is a detail view of a modified form of the device wherein the frame is collapsible, and Fig. 7 is an end view of said device.

Like reference characters indicate like parts throughout the drawings.

Referring to the drawings and first to Figs. 1 and 2, 10 is an arm or bar made of any suitable material, such as wood, metal, rubber or the like, and of any desired contour and cross section, here shown as square. The bar 10 is adapted to be held and manipulated by the operator, either with one or both hands. The bar may be made of any desired length; for example it may be so short as to embrace only the tones within the compass of the musical triad intervals formed by chord root, third and fifth in closest succession, etc., or long enough to embrace all or any of the tones of the same triad, repeated and distributed, as desired,

in as many octaves as the length of the keyboard of the instrument will permit. In the particular embodiment of my invention illustrated, the bar 10 is provided with a plurality of fingers or hammers, here illustrated as seven in number, preferably projecting at right-angles from the bar 10, and indicated at 11, 12, 13, 14, 15, 16 and 17, respectively. These fingers are preferably arranged in substantially the same plane, and so project from the bar 10 that when the latter is held in the correct position for playing on the keyboard, the fingers extend downwardly from the bar towards the keyboard, so that when the bar is depressed, either by moving it parallel to itself towards the keyboard, or by rocking the same, the fingers may be brought into engagement with the keys and act as plungers to depress the same and produce the desired tones.

One of the fingers 11, which I shall term the bass finding finger, is preferably of a different character from the other fingers, and in the embodiment illustrated is shorter than any of the other fingers, and is preferably attached to the bar near one end thereof. The remaining finger or fingers are spaced from the bass finder so as to depress desired keys on the keyboard when the device is properly manipulated either by rocking the same or moving the bar 10 parallel to itself. In the embodiment illustrated, these six fingers are arranged in groups, and here illustrated as three groups, which I have indicated generally at 18, 19 and 20, with two fingers in each group, although it will, of course, be understood that the grouping may be differently arranged and, in fact, other fingers could be inserted. In the particular embodiment illustrated, each group comprises two fingers, the group 18 comprising the fingers 12 and 13, the group 19, the fingers 14 and 15, which are preferably longer than the fingers 12 and 13, and the group 20, the fingers 16 and 17, the finger 16 preferably being of substantially the same length as the fingers 14 and 15, while the finger 17 is somewhat shorter. All of the fingers of the three groups are preferably relatively long as compared with the bass finder, the fingers of each group being so spaced apart as to produce tones harmoniously related when the said fingers depress keys of said keyboard. In the form illustrated, when the bass finding finger 11 depresses a given key

of the keyboard, for example, the key C of the C major scale, then the musical interval from the tone produced by the key C to that which is produced by the key which is 5 depressed by finger 12 is a major tenth, from 12 to 13 a minor third, from 13 to 14 a major six, from 14 to 15 a minor third, from 15 to 16 a perfect fourth, and from 16 to 17 a major third.

10 Each of the fingers is preferably provided with a tip 21 formed of suitable yielding material, such as rubber, in order better to simulate the action of the tips of the fingers of the human hand.

15 An additional finger 22 is also preferably provided, which also preferably projects at right-angles from the arm or bar 10, but in a different plane from the remaining fingers and for a purpose which will herein- 20 after appear.

In Fig. 5, I have illustrated a modified form of finger, which is adjustable with reference to the bar 10, in which it is mounted, the finger preferably being screw-threaded, 25 as at 23, for at least a portion of its length, the screw-threads engaging corresponding screw-threads formed on the interior of the opening 24 in the bar 10, through which the finger passes. It will, of course, be understood that all or any of the fingers may 30 be made adjustable. It will, of course, be understood that whether the fingers are adjustable or fixed with reference to the bar 10, they are preferably readily detachable 35 to facilitate disassembly of the device for purposes of packing.

In Fig. 6, I have shown a further modification of my invention wherein the bar 10^a is made collapsible, in order further to facilitate packing the device. In the form here illustrated, the bar 10^a is formed of a plurality of sections, here shown as two in number, 10^b and 10^c, respectively, one of the sections, such as 10^b preferably being 45 provided at one end with a ferrule 25, which is telescopically received in a suitable socket 26, secured on the end of the other section 10^c.

The operation or manipulation of the said 50 device will readily be understood from the foregoing description as follows: Assume that the device is to be used in conjunction with the white keys of the keyboard, in which case it is kept in a plane substantially 55 parallel to the front of the instrument, as illustrated in Fig. 1. By tilting the device so that the left hand end thereof is lower than the other end, as illustrated in Fig. 1, the comparatively short bass finding finger 60 11 is caused to depress a key of the keyboard to produce the desired bass tone. The bass tone determines the chord which is to be produced by the remaining fingers. By 65 suitably manipulating the said device, one or more other tones can also be produced

harmoniously related to the bass tone. For example, after the bass tone is struck by the finger 11, by tilting the device the finger 12 may be caused to depress a key and produce a tone separated from the bass tone by the 70 musical interval of a tenth, so that the two tones are harmoniously related and produce a chord interval. Usually, however, a plurality of keys are depressed to produce a full chord. This may be done merely by 75 bringing both fingers 12 and 13 of the group 18 into engagement with two keys, so that these two keys, together with the key depressed by the bass finder 11 will produce a musical triad. The remaining fingers 14, 80 15, 16 and 17 are preferably so arranged as to produce repetitions of the tones of the triad in a higher octave or octaves, the tone produced by the bass finding finger being the fundamental tone of the chord produced 85 by the remaining fingers. Obviously, by suitably manipulating the device, the chord can be produced in different combinations and positions. For example, after the two 90 fingers 12 and 13 have depressed the two corresponding keys of the keyboard, which will be the keys E and G when the bass finder 11 has depressed the key C, then by further tilting the device, the two fingers 14 and 15 may be made to depress the keys E 95 and G, an octave above the keys depressed by the fingers 12 and 13. By still further tilting the device, the fingers 16 and 17 will depress the keys C and E of the keyboard, the key E being located an octave 100 above the key depressed by the finger 14. Obviously the tilting movement of the device may be reversed, thereby repeating the chords in any desired manner. It will, of course, be understood that after the bass 105 tone has been played, the bar may be moved parallel to itself, thereby causing the remaining fingers simultaneously to depress corresponding keys.

By slanting the device with respect to 110 the front of the musical instrument with which it is used, both the white keys and the black keys can be used. For example, the bass finding finger 11 may be brought into engagement with the white key, such 115 as D, as illustrated in Fig. 2, and the modulating finger 12 will then depress a black key.

The device may be used by an operator 120 possessing little musical skill, it being necessary for him only to select the correct bass tones, and this ability is usually quickly acquired. In accordance with my invention, however, means are preferably provided for affording to those, either with or without 125 musical skill or training, an indication of the manner in which the device is to be used. In Figs. 1, 2 and 3 are illustrated what I shall term a "bass indicator chart", which I have indicated generally at 27. The chart 130

may be made from cardboard or other suitable material, and is provided with projecting fingers 28, 29, 30, 31, 32 and 33, the successive fingers being spaced apart a distance 5 corresponding to the width of the black keys of the keyboard, so that when the chart is placed in position with the black keys received in the spaces between the said fingers, the fingers will lie over the white keys of 10 the keyboard. The projecting fingers are suitably designated to represent the tones of the underlying keys of the keyboard of the C scale, showing the seven tones of the C major scale. For this purpose, the fingers 15 28 and 29 are preferably designated 1 and 2, the finger 30, which overlies the two keys E and F of the keyboard is designated 3, 4, the character 3 designating the left-hand portion of the finger, and the character 4 designating 20 the right-hand portion thereof, while the fingers 31, 32 and 33 are designated by the characters 5, 6 and 7, respectively. In the arrangement illustrated, the fingers 28 and 33 are preferably of a width to overlie 25 two keys of the keyboard, it being understood that the left-hand portion of the finger 28 which is designated (7), and the right-hand portion of the finger 33 which is designated 30 (1) (C), are merely repetitions in another octave of fingers already described. In use the rear portion of the chart is bent upwardly along the line 34, drawn along the rear edges of said spaces. Preferably the 35 chart is also provided with characters designating the black keys, as illustrated.

In accordance with my invention, song charts, indicated generally at 35 (see Figs. 40 1, 3 and 4) are provided, on which are written the words of a song, certain words of which are preceded by numbers which correspond to numbers on the bass indicator chart, and which indicate the tones to be 45 played by the bass finding finger of the said device. For example, in Fig. 4 is illustrated in a fragmentary way, a song chart arranged for the song "Old Folks at Home."

In playing the accompaniment for the 50 first words "Way Down Upon the Swannee," the operator would strike the bass finding finger 11 against the key underlying the portion of the projecting finger on the bass indicating chart 27 which underlies the projecting finger 28 of said chart, and which is designated as "1." The operator would then tilt the device to play a chord or chords in the manner above described, and to produce a desired rhythm, the chord 55 being continued until the next number on the song chart is reached. Referring again to the song chart, after the accompaniment has been played for the words "Way Down 60 Upon the Swannee," the operator strikes the key underlying the right-hand portion of 65

the finger 30, which is designated 4 with the bass finding finger 11. This process is repeated in playing an entire selection.

The melody finder finger 22 is used merely for the purpose of playing the tones of a 70 melody, the operation of which is alternated with the operation of the entire device as heretofore described.

The manually-operated device embodying 75 my invention may be manipulated in numerous ways, in order to produce the desired fundamental tones and chords harmoniously related thereto. As stated, the device may be used only on the white keys, in which case it is held in a plane substantially parallel with the front of the musical instrument. The device may also be held parallel to the front of the instrument, all the fingers being located above the black keys, or above the black and white keys, according to the tone played by the bass finding finger. Again the device may be held in a slanted position with the bass finding finger on a white key and the modulating finger 12 on a black key, or with the bass finding finger on a white key, the modulating finger 12 on a black key, and the adjacent finger 13 also engaging a black key. The device may also be held in a slanted position with the bass finding finger on a black key and the modulating finger 12 and the finger 13 adjacent thereto on white keys. The device may also be held in a slanted position with the bass finding finger and modulating finger 12 on white keys with 90 the adjacent finger 13 on a black key. 100

I claim:

1. A manually operated device for playing on the keyboard of a musical instrument, 105 comprising a plurality of projecting fingers of different character in a single plane for engaging the keys of said keyboard.

2. A manually operated device for playing on the keyboard of a musical instrument, 110 comprising a plurality of substantially parallel projecting fingers of differing lengths for engaging the keys of said keyboard.

3. A manually operated device for playing on the keyboard of a musical instrument, 115 comprising a plurality of fingers projecting in a single plane for engaging the keys of said instrument, one of said fingers being of a different character from the others.

4. A manually operated device for playing on the keyboard of a musical instrument, 120 comprising a plurality of fingers projecting in a single plane for engaging the keys of said instrument, one of said fingers being of a different length from the others.

5. A manually operated device for playing on the keyboard of a musical instrument, 125 comprising a comparatively short finger for singly depressing one of the keys of the instrument, and a plurality of longer fingers substantially parallel to said short finger 130

- and different therefrom in length for depressing a plurality of keys.
6. A manually operated device for playing on the key board of a musical instrument, comprising a comparatively short finger for singly depressing one of the keys of the instrument to produce the fundamental tone of a chord, and a plurality of comparatively long fingers spaced apart to produce other tones of the same chord on the keys of said keyboard when depressed by said comparatively long fingers.
7. A manually operated device for playing on the keyboard of a musical instrument, comprising a comparatively short finger for singly depressing one of the keys of the instrument, and a plurality of comparatively long fingers of substantially the same length, all of said fingers being substantially parallel.
8. A manually operated device for playing on the keyboard of a musical instrument, comprising a comparatively short and a comparatively long finger, the two fingers being in a single plane and so spaced apart as to depress two keys of said keyboard to produce tones harmoniously related.
9. A manually operated device for playing on the keyboard of a musical instrument, comprising a comparatively short finger for singly depressing one of the keys of said keyboard, and a plurality of groups of fingers for depressing corresponding keys of the keyboard, all of said fingers being substantially parallel.
10. A manually operated device for play-
- ing on the keyboard of a musical instrument, comprising a comparatively short finger for singly depressing one of the keys of the instrument, and a plurality of groups of fingers for depressing corresponding keys of the keyboard, the fingers of each group being spaced apart to produce a desired musical interval, all of said fingers being substantially parallel.
11. A manually operated device for playing on the keyboard of a musical instrument, comprising a plurality of groups of fingers of different lengths substantially parallel to each other, the several groups being constructed and arranged to depress the keys of the keyboard either successively in groups or simultaneously depending upon the manipulation of the device.
12. A manually operated device for playing on the keyboard of a musical instrument, comprising an arm or bar provided with a plurality of substantially parallel fingers of different lengths.
13. A manually operated device for playing on the keyboard of a musical instrument, comprising a plurality of fingers for depressing the keys of a piano, each finger being provided at its end with a telescoping yielding cap.
14. A manually operated device for playing on the piano or the like, comprising a plurality of fingers of different lengths projecting in one plane and a single finger projecting in a different plane.

DAVID TALMAGE.
